COLLOIDAL GRAPHITE SUSPENSIONS

Otto Albrecht Graf von Mandelsloh, Dresden,
Germany, assignor to the firm Chemische Fa-
brik Florsheim vorm. Dr. H. Noerdlinger Ak-
tiengesellschaft, Florsheim-on-the-Main, Ger-
many

Application December 21, 1933, Serial No. 703,486
In Germany December 29, 1932

2 Claims.

(Cl. 87—9)

As is known graphite finds many applications in the lubricant art. Now whilst graphite is suitable as it stands for rough lubrication—i. e., for example for the lubrication of vehicles or the like—various difficulties occur in the case of its employment for fine lubrication. Methods are already known by means of which the graphite is chemically suspended in mineral oil. These known methods for the production of colloidal graphite suspensions are, however, rather expensive; they require a large plant and in this case a considerable loss of graphite is unavoidable.

The present invention relates to a method for obtaining colloidal graphite suspensions mechanically. Now whilst it is not possible to obtain colloidal graphite suspensions with colloid mills or ordinary multiple-roller mills, it has been found that the production of colloidal graphite suspensions is effected when according to the invention the graphite mixed with a liquid binding agent, preferably a thinly fluid mineral oil, to form a paste is triturated under extremely high pressure in single-roller and multiple-roller mills, triturating mills, and like mills with surface trituration.

For normal trituration of pigments or the like in oils, fats, or the like such a high pressure cannot be employed because if it were the rollers would immediately run hot. It is only owing to the fact that the graphite to be triturated acts at the same time according to the invention as a valuable lubricant that it is possible to employ a specially high pressure.

For carrying out the present method there may be used for example a so-called single-roller mill. As is known, single-roller mills have a single triturating roller, over which, for producing a trituration over as large a surface as possible, a triturating bar of a width of several centimetres is moved to and fro. Such single-roller mills are very sensitive as regards the pressure of the triturating bar on the triturating roller. In the case of thin material to be triturated that is poor in fat there occurs at the slightest over-pressure a grinding of the triturating bar on the triturating roller so that the machine is immediately brought to rest and the roller is badly injured. Even in the case of the employment of masses that are rich in fat the pressure of the triturating bar on the triturating roller is limited because when the pressure is great the triturating bar presses the lubricant away from the roller so that the disadvantages hereinbefore mentioned arise.

In the case of the employment of graphite sus-
pensions these phenomena do not occur. The
triturating bar can be pressed upon the triturat-

ing roller with the greatest pressure that can be technically exerted, and whereas in the case of previous single-roller mills the highest pressure that can be employed is 150 to 200 grammes per square millimetre, according to the invention in the case of the trituration of graphite suspensions the pressure may be raised to 1.5 to 2.0 kilogrammes per square millimetre—i. e. to about ten times the amount. Only in the case of the employment of this pressure are the graphite particles, especially when the graphite paste is passed repeatedly through the machine continually more and more crushed and assume in the course of the grinding or trituration process the desired colloidal condition.

Multiple-roller mills may also be used for the production of colloidal graphite suspensions according to the invention; but in that case the following points must be observed.

In the case of ordinary roller mills with several rollers there occurs only a linear trituration of the material to be ground, which is not sufficient for the colloidal comminution of the graphite. When a large over-pressure is used in the case of these multiple-roller mills, there occurs a breaking of the rollers, which, even if hardly measurable, destroys their linear contact and consequently their action.

Now it has been found that even in the case of multiple-roller mills, which otherwise allow only a linear trituration, a surface trituration under high pressure is rendered possible by providing the several rollers with an excessively "crowned" or longitudinally outwardly curved surface. Ordinarily the curvature or spherical polishing, which is measured with optical instruments, amounts to 10μ . According to the invention the curvature or spherical polishing of the rollers is increased to five times—i. e. to 50μ .

The excessive spherical polishing of the triturating rollers enables the necessary pressure to be applied in such a manner that instead of the trituration occurring as otherwise in ordinary multiple-roller mills only linearly, which is not sufficient for a colloidal comminution of the graphite even when the strongest pressure is employed, there occurs a much more effectual surface trituration. The surfaces of contact between the several rollers are in consequence of the high pressure and of the exaggeratedly curved surface no longer linear but spindle shaped, corresponding to the cross-section of a bi-convex lens. In the case of roller mills with several rollers it is advisable also to give individual rollers a considerably higher rotational velocity than the other

rollers, so that the rollers not only act on the material to be ground coming between them so as to crush it but also exert a rubbing action.

The variation of the rotational velocities of the several triturating rollers from one another is impossible in the case of the employment of ordinary material to be ground, because if it were employed the rollers would run hot and grind in a very short time notwithstanding water cooling.

10 This differential increase of the rotational velocity of individual triturating rollers is rendered possible only by the exercise of the lubricating force of the graphite to be colloidally triturated.

15 Of course, for triturating the graphite, instead of mineral oils of low viscosity there may be employed highly viscous materials, for example aqueous or fatty materials, of any desired kind.

In the annexed drawing:

20 Fig. 1 is an elevational view of a pair of conventional grinding rollers *b* and *c*, having bearing portions *a*, illustrating the rollers in idle condition in line contact;

25 Fig. 2 is a view similar to Fig. 1, but illustrates the rollers in operation, with material passing through them and shows, to an exaggerated extent, how the rollers flex away from each other and form a clearance *d* under the influence of the wedge formed by the material.

30 Fig. 3 is an elevational view of a pair of rollers *b'* and *c'* of the character preferably used for carrying out the present invention and wherein the rollers are spheroidal in form. The deviation from cylindrical form is comparatively slight and is in the neighborhood of 50μ , but it has been exaggerated in the drawing so as to more 35 clearly illustrate the feature involved. The letter *e* designates the deviation from a true cylindrical roller;

35 Fig. 4 is a view taken on the line 4—4 of Fig. 3 and illustrates diagrammatically the areas of the rollers that are disposed in surface engagement when the pressure is applied thereto. These areas define a triturating zone wherein the graphite mixture is subjected to a pressure of approximately 1.5 to 2.0 kilograms per square 40 millimeter.

It has been found that specially durable suspensions of graphite can be obtained if the graphite ground in the ordinary manner is first 45 mixed by stirring with blown or thickened fatty oils or so-called mineral oil-soluble castor-oil and left to swell for several hours and the graphite paste is then subjected in the hereinbefore-described manner to a fine grinding with surface trituration under high pressure. The 50 colloidal graphite thus produced has a considerably longer capacity for suspension in mineral

oils than graphite ground only with mineral oils.

It has further been found that in the presence of quantities of graphite that are only so large that the employment of a surface trituration under high pressure is rendered possible, it is also possible to convert other materials, for example colour pigments, clays, soot, in a short time into an extraordinarily fine colloidal distribution by means of the hereinbefore-described grinding under high pressure.

10 It is also advisable for the colloidal distribution of the graphite according to the invention to employ roller mills in which the bearings of the triturating roller can swing freely. For the colloidal distribution of the graphite therefore 15 single-roller mills provided with triturating bars are specially suitable in which the bearings of the triturating roller are not fixed in the machine frame but are arranged therein so as to be vertically movable and in which the triturating 20 roller bears against a counter triturating bar which is fixed in the machine frame and receives the pressure of the triturating bar which is provided over the triturating roller in the ordinary way. In this case the bearings of the triturating 25 roller remain entirely without pressure so that unrestrictedly high pressures can be applied. Instead of one triturating roller there may be provided several triturating rollers arranged vertically one above another, the lowest roller then 30 resting on the counter triturating bar.

Instead of the triturating bar and the counter triturating bar pressure rollers which run in roller bearings or the like may be employed.

35 I claim:—

1. The method of producing a colloidal graphite suspension which comprises mixing graphite with a suspending medium and introducing the mixture between at least two spheroidal shaped rollers and simultaneously forcing said rollers together under sufficient pressure to deform their cylindrical walls into surface engagement to define a high pressure triturating zone and subject said graphite mixture to a pressure of approximately 1.5 kilograms per square millimeter, 45 and rotating said rollers so as to triturate said mixture and break the leaves of said graphite in directions substantially normal to their major axes and bring the graphite into colloidal form, 50 the area of engagement of said cylindrical walls being sufficiently great to preclude inadvertent escape of said graphite leaves from the triturating zone under the influence of said pressure.

2. The method described in claim 1, wherein the curvature of said spheroidal shaped rollers is approximately 50μ .
